A. A. CRUSIUS,
AUXILIARY INLET VALVE FOR INTERNAL COMBUSTION ENGINES.
APPLICATION FILED DEC. 18, 1916.

1,278,863.

Patented Sept. 17, 1918.

Arthur A. Crusius, Inventor

By his Attorney

UNITED STATES PATENT OFFICE.

ARTHUR A. CRUSIUS, OF NEW YORK, N. Y.

AUXILIARY INLET-VALVE FOR INTERNAL-COMBUSTION ENGINES.

1,278,863.

Specification of Letters Patent. Patented Sept. 17, 1918.

Application filed December 18, 1916. Serial No. 137,539.

To all whom it may concern:

Be it known that I, ARTHUR A. CRUSIUS, a citizen of the United States of America, residing at New York city, county and State of New York, have invented certain new and useful Improvements in Auxiliary Inlet-Valves for Internal-Combustion Engines, of which the following is a full, clear, and exact description.

10 This invention relates to improvements in auxiliary air-inlet valves arranged for attachment to the intake manifold of an internal combustion motor. My improved device not only comprises an automatic valve, 15 but also a gasket-plate to which the valve is attached, said gasket-plate being arranged to be positioned between the flanges of a carbureter and intake-manifold. My improved valve has for an object to provide a 20 means whereby air can be drawn into a motor and mixed with the combustible mixture from the carbureter, at a certain engine speed; that is to say, my improved valve is arranged so that it will automatically open 25 to admit air to the intake-manifold, after the engine has attained a speed of say (for instance) ten miles per hour, whereby a rich combustible mixture will be provided. My improved valve will admit air to the intake- 30 manifold in excess of the air drawn in through the carbureter, it being well known that an auxiliary supply of air is highly beneficial to the operation of an internal combustion motor.

35 I will now proceed to describe my invention in detail, the essential features of which will be summarized in the appended claim, reference being had to the accompanying drawing, forming part hereof, 40 wherein:

Figure 1 is a diagrammatic side view of a portion of a carbureter and intake-manifold of an internal combustion motor, my improved valve being illustrated as attached 45 thereto;

Fig. 2 is an enlarged detail view of my improved combination of gasket and air-inlet valve; and

Fig. 3 is an enlarged cross sectional view, 50 the section being taken on a line 3-3 of Fig. 1.

As herein illustrated, my invention consists partly of a gasket-plate 1 arranged for insertion between the flanges 2 and 3 of an 55 intake-manifold 4 and carbureter 5, respectively (see Fig. 1), the said gasket-plate be-

ing provided with an opening 6 to register with the ducts of the carbureter and manifold, said gasket-plate being also provided with openings 7 for the passage of bolts 8. 60 The other element of the combination consists of a valve casing 9 having an extension 10 provided with a duct 11 communicating with the chamber 12 in the casing 9. The lower part of the casing carries a nipple 13 65 provided with a duct 14 communicating with the chamber 12. The duct 14 is closed by a ball-valve 15 which seats on a valve-seat 16 surrounding the duct 14.

To regulate the lift of the valve 15, by the 70 suction of the pistons, I employ a threaded rotatable spindle 17 provided with a seat 18 at its lower end, said seat having a concavity 19 to fit the ball or valve 15. The spindle 17 passes through a threaded bushing 20 and 75 carries a lock-nut 21.

The casing 9 is secured to a duct 22, carried by the gasket-plate 1, by means of a union consisting of a nut 23 which engages the threads on the enlargement 24 of the extension or neck 10. The outer end of the enlargement of the neck 10 is tapered to 80 form a valve 25 to co-operate with a seat 26 in the flanged end 27 of the duct 22.

The union referred to performs the function of securing the duct 22 and valve casing 9 together, and also to provide a means whereby the said duct and valve casing can be rotatably connected without the necessity of unscrewing the nut 23. To adapt the 85 union for the latter function, I provide a lock-nut 28, which, after the nut 23 has been screwed up to firmly connect the parts, can be jammed against the said nut 23, thereby locking the nut and neck 10 together, and 90 hence the valve can be rotated without the necessity of unscrewing the nut 28 and also without the danger of loosening the connection between the parts.

The valve casing 9 is preferably arranged 100 for rotatable adjustment in order that it can be caused to assume a perfectly vertical position, thereby causing the valve 15 to properly seat.

The nipple 13 is provided in order that a 105 pipe 29 can be connected thereto for the purpose of introducing water, or other carbon removing liquid, into the motor while it is running and warm.

When a pipe such as 29 is connected, water or other liquid, can be drawn into the motor, by the suction of the pistons, simulta- 110

neously with the combustible mixture. Should I desire to shut off the auxiliary air supply, I simply screw the spindle 17 down against the valve 15 and lock same by means 6 of the nut 21.

The valve and gasket will be preferably supplied in combination, but the casing 9 can be secured directly to the manifold if desirable. However, I prefer the combination as herein illustrated and described, as the operation of installation will thereby be greatly simplified.

What I claim is:

In combination with a gasket, adapted to 15 be fastened between an intake manifold and a carbureter, and having a lateral opening communicating with the passage between these two elements, a duct fitting into said opening and having an annularly flanged 20 outer end which is concave in its exterior face, a coupling nut sleeved on said duct behind said flanged end and prevented from

pulling over the latter, an automatic air inlet valve, a valve-casing therefor provided with a lateral duct adapted to screw into said 25 nut, the connection between these two latter elements permitting the turning of said casing and valve to secure perfect vertical positioning of said casing and accurate seating of the valve, this lateral duct of the casing 30 being provided with a convex end, which fits the concavity of the first named duct, and also with a lock nut, bearing against said coupling nut, the said parts being adapted to permit the turning of said casing without 35 unscrewing said lock-nut or loosening said coupling nut from the ducts.

Signed at New York city, N. Y. this 16 day of December, 1916.

ARTHUR A. CRUSIUS.
